DIE CASTING MACHINE

Jakob Vontobel, Teufenthal, Switzerland, assignor to the firm Injecta Aktiengesellschaft, Teufenthal, Canton of Aargau, Switzerland, a joint-stock company of Switzerland

Application July 7, 1937, Serial No. 152,406
In Germany August 7, 1936

3 Claims. (Cl. 22—68)

The present invention relates to die casting machines for manufacturing dense castings from alloys having a high melting point. With such metals the hitherto known methods of die casting cannot be easily employed. The use of such metals in a liquid state proved to be wasteful on account of the corroding and wearing away of the moulds. Therefore machines were proposed having a cold chamber into which the metal was introduced by hand in a pasty state. But then with this half liquid metal also slag would be filled in. Moreover, the metal would solidify at the gate, for the gate is necessarily highly constricted to facilitate breaking the waste from the casting. This fact and the tenacity of the metal had a bad influence on the forming of the surfaces and the texture of the castings. The castings were characterized by porosity and even large holes and cavities. It has already been proposed for die castings made of low melting alloys to act with several pressures of different amount upon the metal while solidifying in the mould in order to improve the texture of the same. Different pressures were employed for the introducing and afterwards for the compressing. But for high melting alloys this method won't do, because it is hardly possible to conceive control apparatus which can exactly follow the solidifying process within the mould.

With the method according to the present invention the effect of two successive different pressures is obtained with only a single source of pressure by a contrivance by which, although the metal is employed in a very liquid state, resistances to flow are used which retard the filling of the form up to the beginning of the pressure of the piston, with the purpose to carry the pressure on the liquid metal by the piston only to a pressure adapted to overcome the static pressure of the metal filling the mould. Thus after having filled the mould softly and with an even speed the high pressure of the piston becomes then effective and compresses the metal in the mould by utilizing part of the metal in the inlet.

The annexed drawings represents schematically as an example a casting machine for a T pipe fitting.

Fig. 1 is a vertical section of the mould and Figs. 2 and 3 are side and end elevation on a smaller scale of a casting machine.

According to the drawings the mould box is attached to a pedestal 2 mounted upon a bedplate 1. The mould box is in two parts and comprises a stationary plate 3 cast in one piece with the pedestal and carrying bolted thereto one half 4 of the mould and further comprises a movable plate 6 slidably held on four rods 5 secured to said standard. The other half 7 of the mould is fast to plate 5. The mould, a chill, has, besides the mould 10 and the holes 19 for the pilot pins, also guides 8 for the cores 9 and an inlet conduit 11 intended as a storage and pressure chamber. This inlet conduit includes also an intermediate chamber or enlargement 34 separated from the inlet 10 and the mould by two restricted passage ways 33 and 35, the latter branching off sideways and forming the direct inlet of the mould. The inlet orifice 12 is conically enlarged. The mould and the inlet passages are provided with holes 13 for the ejector pins.

The movable mould plate 6 is connected by means of stays 14 with a pusher plate 16 and between these two plates are slidably arranged, on one side the core plate 17 and on the other side the ejector plate 18. The operating of the pusher plate 16 and thereby the opening and closing of the mould is effected by means of a knee joint mechanism 22.

A median rod 20 carries slidably mounted thereon a cross bar 21 to which are linked two links 22 which are linked with their free ends to the joints of two jointed pairs of toggle arms 24 linked to the pusher plate 16 and to the stationary guide block 23. If the cross bar is moved toward the right from the position shown, the two toggle pairs of arms 24 will bend and open the mould. If the cross bar moves in a contrary direction the mould will be closed, as shown in the drawing. The mould can also be opened and closed by other means than the toggle mechanism here illustrated. The guide block 23 is bolted to the bedplate 1.

The pressure cylinder 25 with the piston 26 is carried by the pedestal 2. The pressure cylinder 40 may be displaced in two directions by means of the slides 31, 32 and the screw spindles 29 (Fig. 2), 30 (Fig. 3). Thus the piston 26 may be adjusted to be co-axial with the inlet pipe or pressure chamber 11 in the case of differently sized moulds. The piston is withdrawn so far from the inlet conduit 11 during the introducing of the metal, that the metal may be easily poured in by means of a ladle or otherwise.

The machine is operated as follows: 50

When the machine is at rest the mould is open and the piston 26 withdrawn from the inlet 11. The cores 9 are inserted into the movable half of the chill. In this condition the mould will be closed by operating the piston rod 20 and asso- 55

ciated toggle mechanism, whereupon the metal in a very liquid state is filled into the inlet conduit 11 by means of a ladle. Immediately after this the piston 26 will be introduced into the inlet conduit and the still liquid metal, which has been checked from the immediate admission into the mould by the restricted passage ways 33, 35 and the intermediate chamber 34, will be pressed into the mould by a pressure of the piston which pressure will be maintained unto the complete solidifying of the metal. During this operation all air will escape through the vents 28 while impurities, slag and the like, are retained by the restricted passage ways of the inlet.

15 When the metal has been completely solidified the mould is opened and the casting expelled by the ejector pins. In this way a rapid delivery of castings may be obtained. In consideration, that the mechanism for the timed moving of piston 26, pusher plate 16, core plate 17 and ejector plate 18 and core screws 27 may be supposed to be well known and may be arranged in different ways, such mechanism has not been shown in detail.

25 What I claim as new is:

1. Apparatus for single shot die-casting of manually ladled high temperature alloys in liquid condition, said apparatus comprising a die having a mold cavity, a generally upright pressure chamber communicating with a conventional highly constricted gate formed at the mold cavity, the communication between the pressure chamber and the gate including alternate constrictions and enlargements suitably dimensioned to retard the initial flow of metal from the pressure chamber to the gate, there being two constrictions with an abrupt and substantial enlargement therebetween, all in addition to the aforesaid constricted gate, a plunger, means to reciprocate the same into and out of the pressure chamber, said plunger being fully retractable from the pressure chamber in order to facilitate manual ladling of a quantity of the liquid metal into the pressure chamber, and means to eject the solidified residue from the pressure chamber, the enlargement, and the die cavity, said pressure chamber being higher than the gate, whereby the metal when first ladled therein would, if unobstructed, quickly flow to the gate, the arrangement acting to retard the initial flow of the metal.

2. Apparatus for single shot die-casting of manually ladled high temperature alloys in liquid

condition, said apparatus comprising a die having a mold cavity, a generally upright pressure chamber communicating at its lower end with a conventional highly constricted gate formed at the bottom of the mold cavity, whereby the metal being cast flows downwardly, sidewardly, and then upwardly into the mold cavity, the communication between the pressure chamber and the gate including alternate constrictions and enlargements suitably dimensioned to retard the initial flow of metal from the pressure chamber to the gate, there being two constrictions and two enlargements, all in addition to the aforesaid constricted gate, a plunger, means to reciprocate the same into and out of the pressure chamber, 15 said plunger being fully retractable from the pressure chamber in order to facilitate manual ladling of a quantity of the liquid metal into the pressure chamber, and means to eject the solidified residue from the pressure chamber, the enlargements, and the die cavity, said pressure chamber being higher than the gate, whereby the metal when first ladled therein would, if unobstructed, quickly flow to the gate.

3. Apparatus for single shot die-casting of manually ladled high temperature alloys in liquid condition, said apparatus comprising a die having a mold cavity at the parting face, a generally upright pressure chamber also formed in the die at the parting face and communicating at its lower end with a conventional highly constricted gate formed at the bottom of the mold cavity, whereby the metal being cast flows downwardly, sidewardly, and then upwardly into the mold cavity, the communication between the pressure chamber and the gate including alternate constrictions and enlargements formed in the die at the parting face and suitably dimensioned to retard the initial flow of metal from the pressure chamber to the gate, there being two constrictions and two enlargements all in addition to the aforesaid constricted gate, a plunger, means to reciprocate the same into and out of the pressure chamber, said plunger being fully retractable from the pressure chamber in order to facilitate manual ladling of a quantity of the liquid metal into the pressure chamber, and means to eject the solidified residue from the pressure chamber, the enlargements, and the die cavity, said pressure chamber being higher than the gate, the arrangement being devoid of mechanical valves or the like to obstruct the flow of metal.

JAKOB VONTOBEL.
